UNITED STATES PATENT OFFICE

WILLIAM E. WINE, OF TOLEDO, OHIO

RAILWAY CAR

Application filed March 28, 1929. Serial No. 350,666.

My invention relates to railway cars and more particularly to improvements in the construction and arrangement of the body bolster and associated parts.

5 A principal object of the invention is to produce a body bolster of simple and rugged construction especially suitable for application to drop bottom railway cars having an inclined floor sheet.

10 A further object of the invention consists in providing the bolster with improved means to which car side stakes may be attached.

Another object of the invention is to provide a sectional bolster with integral means whereby the parts thereof may be rigidly connected.

15 A primary feature of the invention consists in providing a bolster having a top flange with end flanges projecting upwardly above adjoining portions of the top flange.

20 Another feature of the invention resides in constructing a body bolster with a top flange and with members projecting upwardly therefrom adjacent its opposite ends, each of said members having portions to which a car side stake and a car side sheet may be respectively secured.

25 A still further feature of the invention consists in providing the body bolster with upwardly projecting substantially Z-shaped members adjacent its opposite ends.

30 A still further feature of the invention resides in constructing the body bolster in sections and in providing each with integral upstanding plate-like extensions which overlie the center sill and which may be rigidly connected in overlapping relation.

35 Other and more specific features residing in advantageous forms and combinations and relations of parts will hereinafter appear and be pointed out in the claims.

In the drawings illustrating a preferred embodiment of the invention:

40 Figure 1 is a transverse vertical sectional view of a railway hopper car, the bolster being in elevation,

45 Figure 2 is a plan view of the body bolster,

50 Figure 3 is an enlarged sectional view taken on line 3—3, Figure 1,

Figure 4 is a fragmentary sectional view taken on line 4—4, Figure 3,

Figure 5 is a fragmentary sectional view taken on line 5—5, Figure 3,

Figure 6 is a perspective view of a portion 55 of the car construction adjacent one of the ends of the bolster, the inclined floor sheets being detached from the bolster and car side sheets,

Figure 7 is a fragmentary sectional view 60 taken on line 7—7, Figure 3,

Figure 8 is a fragmentary sectional view taken on line 8—8, Figure 7,

Figure 9 is a side elevational view of positions of the adjoining ends of the bolster 65 sections, the sections being separated longitudinally,

Figure 10 is an enlarged sectional view taken on line 10—10, Figure 1,

Figure 11 is an enlarged sectional view 70 taken on line 11—11, Figure 1.

Referring more particularly to the drawings 1 indicates the car side sills and 2 the car center sills. Each of the side sills if desired may be formed in sections, one of the sections extending between the body bolsters of the car and the other sections extending respectively between the body bolsters and the adjacent car ends. The car center sills are of usual design, each having a web 3 and 75 upper and lower flanges 4 and 5, respectively. The upper flanges are preferably rigidly connected by a top cover plate 6 and the lower flanges may be rigidly connected by a bottom cover plate 7. Interposed between the center sills is the usual center casting 8.

The body bolster, generally designated by the reference character 9, is formed of a plurality of sections 10 preferably of cast steel. 90 Since the two bolster sections are of substantially identical construction corresponding parts of each section will be designated by similar reference numerals. The bolster sections are respectively interposed between the side sills 1 and the center sills 2 and each is formed with a substantially vertical main web portion 11 and with top and bottom flanges 12 and 13, respectively, which project on opposite sides of the web. The ends of

95 each of the sections are also formed with 100 flanges 14 and 15, respectively, which project on opposite sides of the web. The ends of each of the sections are also formed with

flanges projecting on opposite sides of the webs, the outer flange 14 affording means for rigidly connecting the section to the adjoining side sill by rivets 15 and the inner flange 16 affording means for rigidly connecting the section to the web 3 of the adjoining center sill by rivets 17. The top and bottom flanges of the sections are tied together by a plurality of diagonal truss-like flanges 18 which are arranged to most effectively resist those forces to which the bolster is subjected. The diagonal flanges adjacent the inner ends of the sections respectively merge into the inner flanges 16 thereof. To reduce the weight of the sections the portions of the webs intermediate the diagonal flanges and adjacent portions of the top and bottom flanges may be apertured as at 19.

Projecting inwardly of the opposite sides of the car center sills from each of the bolster sections is an upstanding plate-like integral extension 20 interposed between the floor sheets of the car and the top of the center sills. These extensions project preferably somewhat beyond the side of the center sill opposite the one to which the sections are respectively secured, the extensions being overlappingly connected by rivets 22. Each of the extensions lies in a plane substantially parallel with the web 11 of the section of which it is a part being slightly offset therefrom in order that the plane of engagement of the two extensions may lie in the longitudinal median line of the two sections.

The upper edges of each of the extensions terminate in laterally projecting flanges 23, respectively disposed in planes parallel to adjoining portions of the top flange 12, the flange 23 of one section projecting in a direction opposite to that of the flange of the other section. Thus, when the sections are connected, the flanges 23 form, in effect, one flange constituting a continuation of the top flange 12 of the sections. The lower edge of each extension inclines downwardly toward the section of which it is a part and may be fashioned with a rigidifying flange 24. While each flange 24 projects on opposite sides of the main body portion of the extension 20 the portions of the flanges which project from those faces of the extensions adapted to be brought into contiguous relation extend for only a short distance, merging into the faces of the extensions adjacent the points where they overlap.

Intermediate its ends the top flange 12 of each section is offset as at 25 to receive a plate 26 adapted to overlie the upper surface of the flanges 12 and 23, being rigidly secured to each by rivets 27. The bolster sections, in addition to being connected by the plate 26 may also be connected by the bottom cover-plate 7 of the center sill by rivets 28 which pass through the latter and the bottom flange 13 of the sections. From the foregoing it will

be readily appreciated that each bolster section is secured to adjoining parts of the car structure in a very rigid manner and that they are secured together in a similar manner.

Projecting upwardly above the top flange 12 of the bolster adjacent its opposite ends are angularly shaped members 29. These members are preferably Z-shaped having oppositely projecting flanges 30 and 31 respectively connected by an intermediate or web portion 32. The flange 30 constitutes a prolongation of the adjacent end flange 14 of the bolster, affording additional means to which the adjoining side sheet 33 of the car may be secured as by rivets 34. The web portions 32 of each of the members 29 serve as means to which a car side stake 35 may be secured, the web and side stake being apertured to receive attaching rivets 36. In order that the plane in which the faces of the members 29 and the side stakes 35 contact may be disposed in substantially the median line of the web 11 of the bolster, the web 32 of each of the members 29 is preferably offset slightly from the latter as at 37. The flanges 31 in addition to strengthening the members 29 respectively form with the adjacent side of the car recesses or pockets in which the car side stakes are secured.

Each side stake is preferably of modified channel form having inner and outer flanges 38 and 39, and a web portion 40. The outer flange 39 of the side stake is disposed in substantially the same plane as the end flange 14 of the bolster and the flange 30 of the member 29, thus affording means to which the side sheets 33 and 41 may be overlappingly secured by rivets 42. The side stakes are so designed and are of such size that the inner flanges 38 thereof respectively engage the flange 31 of the upwardly projecting members 29 so that forces subjecting the rivets 36 to shearing strains will be transmitted to the flanges 31 thereby minimizing such shearing strains.

The top flange 12 of the bolster inclines downwardly in a plane parallel to the plane of the inclined floor sheets 43 and 44, the latter being connected thereto by rivets 45. While the portions of the top flange between the webs 32 of the members 29 and the center of the car have respectively the same downward inclination as the main body portion of the top flange 12, those portions of the latter between the webs 32 and the adjacent car end are respectively disposed in an inclined plane substantially parallel to the longitudinal axis of the car to prevent lading within the car from becoming entrapped in the pockets respectively formed by the car floor and flanges 30 and webs 32 of the members 29. The portions of the top flange immediately below the side stakes are cut away so as to form substantially horizontal surfaces 50 affording abutments for the lower ends of the side stakes.

The side edges of each of the floor sheets 43 and 44 are flanged upwardly as at 46 to afford means by which they may be secured by rivets 47 to adjoining portions of the side sheets 41 and 33, respectively. The upturned flanges 46 of the floor sheet 43 may also be secured by rivets 48 to the inner faces of the outer flanges 39 of the side stakes and the upturned flanges of the floor sheet 44 may likewise be secured by rivets 49 to the inner faces of the flanges 30 of the members 29 of the bolsters. Those portions of the floor sheet 44 overlapping the portions of the top flange of the bolster which are disposed in planes forming acute angles 15 with the car sides are fashioned so as to have a similar inclination.

From the foregoing it will be appreciated that the bolster sections are so designed and constructed that they may be rigidly secured 20 together and to the associated parts of the car structure in a most efficient manner.

I claim:

1. A body bolster for railway cars having a web, a top flange formed integrally with 25 the latter and projecting from opposite sides thereof, and portions adjacent the ends of the bolster formed integrally with and projecting upwardly from the top flange intermediate its side edges, said portions respectively 30 affording means to which car side stakes may be attached.

2. A body bolster for railway cars having a top flange and having members projecting upwardly therefrom adjacent its opposite 35 ends, each of said members having a web portion and oppositely projecting marginal flanges, said web portions serving as means to which a car side stake may be secured and one of said flanges affording means to which 40 a car side sheet may be secured.

3. A body bolster for railway cars having upwardly projecting substantially Z-shaped members adjacent its opposite ends.

4. A body bolster for railway cars having 45 a top flange and portions projecting upwardly from the latter adjacent its opposite ends and intermediate its side edges, the portion of the top flange on one side of said upwardly projecting portion lying in a plane substantially normal to the car side and the portion of the top flange on the opposite side of said 50 portion lying in a plane forming an oblique angle with the car side.

5. In a railway car, the combination with a 55 body bolster having a web and a top flange and provided adjacent its opposite ends with portions projecting upwardly from the latter substantially parallel to the said web, of side stakes respectively secured to said upwardly 60 projecting portions, the lower edge of said stakes being disposed above the top flange of the bolster.

6. In a railway car, the combination with a body bolster having an inclined top flange 65 and a substantially vertical web and pro-

vided with portions projecting upwardly above the top flange substantially parallel to the web, of side stakes respectively secured to the said upwardly projecting portions, portions of the top flange adjacent the latter being formed to afford abutments for the lower ends of the said stakes. 70

7. In a railway car having a body bolster provided with a top flange and with members projecting upwardly from the latter adjacent its opposite ends, each of said members having a portion substantially normal to the car side and a portion spaced inwardly from the latter and substantially parallel thereto, and side stakes respectively secured to said members in the angle formed by the said portions thereof. 75

8. In a railway car having a body bolster provided with a top flange and with members projecting upwardly therefrom adjacent its opposite ends, each of said members being of angular shape and forming with the adjacent side of the car a recess for receiving a car side stake. 80

9. A body bolster for railway cars having 90 a web and a top flange and being provided adjacent its opposite ends with portions projecting upwardly above said top flange to which car side stakes may be respectively secured, each of said portions being substantially parallel to the said web and being offset therefrom so that the associated side stake may be secured thereto in substantially the median line of the web of the bolster. 95

10. In a railway car, the combination with 100 a center sill and side sills, of a body bolster formed of a plurality of sections respectively secured to opposite sides of the center and the adjacent side sill, said sections respectively having integral upstanding extensions 105 overlying the top of the center sill and overlappingly secured together.

11. In a railway car, the combination with a center sill and side sills, of a body bolster formed of a plurality of sections respectively 110 secured to opposite sides of the center sill and the adjacent side sill, each of said sections having an integral upstanding extension overlying the top of the center sill and terminating adjacent the side of the center sill 115 opposite the one to which the section is secured, said extensions being overlappingly secured together.

12. In a railway car, the combination with a center sill and side sills, of a body bolster 120 formed of a plurality of sections respectively secured to opposite sides of the center sill and the adjacent side sill, said sections respectively having integral upstanding extensions rigidly connected in overlapping relation above the center sill, the upper edges of said extensions terminating in lateral flanges respectively projecting in opposite directions. 125

13. In a railway car, the combination with a center sill and side sills, of a body bolster 130

formed of a plurality of sections respectively secured to opposite sides of the center sill and the adjacent side sill, said sections respectively having inclined top flanges and integral upstanding plate-like extensions overlying the top of the center sill, said extensions being rigidly connected in overlapping relation and each having an inclined top flange constituting a continuation of the top flange of its section, the top flange of one extension projecting in a direction opposite to that of the top flange of the other extension.

In testimony whereof I affix my signature.
